UNITED STATES PATENT OFFICE.

ROBERT SUCZEK, OF PHILADELPHIA, PENNSYLVANIA, ASSIGNOR TO C. H. WHEELER MANUFACTURING COMPANY, OF PHILADELPHIA, PENNSYLVANIA, A CORPORATION OF PENNSYLVANIA.

EJECTOR SYSTEM.

Application filed February 6, 1922. Serial No. 534,310.

To all whom it may concern:

Be it known that I, ROBERT SUCZEK, a citizen of the United States, residing in the city and county of Philadelphia, State of Pennsylvania, have invented certain new and useful Improvements in Ejector Systems, of which the following is a specification.

My invention relates to an ejector system 10 utilizable in various relations, more particularly for the production and maintenance of vacuum in a steam condenser.

In accordance with my invention, ejector apparatus, either single or multi-stage, has 15 associated therewith an ejector, as an augmenter, for preliminarily raising the pressure of the air or elastic fluid to be compressed or ejected through a preliminary and generally small range of pressure, the motive fluid, as steam, for the augmenter ejector being exhaust steam, such as may be derived 20 from an auxiliary steam engine or turbine employed for driving auxiliary apparatus, as the pump for circulating the cooling water 25 through the main condenser or the condensate removal pump, or both.

Further in accordance with my invention, the augmenter ejector is of such capacity 30 that it is operable by the minimum amount of exhaust steam available, and any excess exhaust steam is automatically diverted.

In accordance with my invention, the 35 ejector system effects high economy as regards total steam consumption in that the augmenter ejector by employment of exhaust steam raises the pressure at the suction of the principal ejector apparatus to such extent that the motive steam, generally live steam, employed in the principal ejector 40 apparatus, required to raise the pressure of the air or other elastic fluid to atmospheric pressure, more or less, is greatly lessened, whereby the over-all steam consumption of the ejector system is lessened.

45 My invention resides in the foregoing and further features hereinafter described and claimed.

For an illustration of one of the various forms my invention may take, reference is 50 to be had to the accompanying drawings, in which:

Fig. 1 is a side elevational view of apparatus embodying my invention.

Fig. 2 is an end elevation, partly in section, of the apparatus shown in Fig. 1. 55

Referring to the drawings, C is the shell of the main condenser, into which exhaust steam, from a main steam engine or turbine, is delivered through the port D and is there- 60 in condensed by coming into contact with and passing between the condenser tubes a, a few of which are indicated in Fig. 2, and through which cooling water is passed, as well understood in connection with surface condensers. The cooling water is supplied 65 to the circulating pump A through the pipe b and discharged through the pipe c into the lower compartment of the end box d, from which it flows through the tubes a of 70 the lower group to the far end of the con- denser C, and then returns through the upper group of tubes a to the upper compartment e of the water box, from which it is discharged through the pipe f.

The condensate of the condenser C collects 75 in the hot well B connected, as by pipe g, with the suction of the condensate-removal pump P and delivered therefrom through the pipe h.

The pumps A and P are driven by the turbine, engine or other steam-driven motor T, to which steam, as live steam, is delivered 80 through the pipe i controlled by the valve j, which is in turn controlled by the automatic centrifugal governor k through the 85 lever m, pivoted at n, as well understood in the turbine art. The exhaust steam from the turbine T is delivered into the pipe o, which communicates with the pipe p delivering 90 exhaust steam to the nozzle structure of the preliminary or augmenter ejector E, here indicated as a tubular ejector whose suction chamber q connects by pipe r with the interior of the condenser C with the 95 space between the tubes a thereof.

The total throat area of the expansion nozzle structure of the ejector E, and the ejector as a whole, is so proportioned that for the minimum amount of exhaust steam from the turbine T, air and other uncon- 100 densed elastic fluid from the condenser C is raised in pressure to small extent, as for example, about one to three inches mercury absolute pressure.

The motive fluid steam in mixture with 105 the air withdrawn from the condenser C is

discharged from the diffuser of the ejector E into the condenser or cooler F of any suitable character, here indicated as a surface condenser in general similar to the main condenser C in that it has tubes through which is circulated cooling medium entering the water box s at t and leaving the water box through the connection u. The cool medium for the condenser F may be derived 5 from any suitable source, as for example, aforesaid pipe e supplied by the pump A. Or the cooling medium may be condensate from the main condenser C, in which case the cooling water system of the condenser F may be connected in the system of the cooling water systems of the condensers G and H hereinafter referred to. Or, and preferably, the cooling water for the condenser F may be the cold make-up water for the 10 feed water of the boiler or steam generators supplying steam to the engines or turbines which exhaust into the condenser C. The discharge from the ejector E passes around the tubes of the condenser F, and the steam 15 is condensed and collects as condensate in the hot well v, from which it may be discharged to any suitable destination, or, as indicated, may be drawn through the pipe w into the hot well B or pipe g containing 20 the condensate of the main condenser C.

In event exhaust steam supplied by the turbine T to the pipe o is in excess of that required or utilizable by the ejector E, the pressure in the pipe o will rise sufficiently 25 to open the check valve x, thereby allowing a portion of the exhaust steam to be bypassed around the ejector E through the pipe y into the condenser F, where it may be condensed separately from or in mixture 30 with the discharge from the ejector E.

Further means may be provided for diverting excess exhaust steam from the ejector E, as by the valve z, controlling egress of exhaust steam from the pipe o through the 35 pipe a¹. The valve z is pivoted at b¹ and attached to the lever c¹, which is biased by the spring d¹ tending to hold the valve z open. In case the load upon the turbine T diminishes, as when the load upon either or both 40 of the pumps A or P diminishes, and particularly when the load upon the pump P diminishes, as when the amount of steam entering the condenser C at D diminishes, the turbine T will increase or tend to increase in speed, and the centrifugal governor 45 will move the upper end of the lever m toward the right and partially close the valve j to diminish the supply of motive steam, and simultaneously the lever c¹ of the valve z will be moved in such direction in opposition to the spring d¹ as to close or partially close the valve z. Conversely, when the load upon the turbine T increases, it supplies a greater amount of exhaust steam, and 50 th, valve z may open and allow escape of

any excess over that required by the ejector E or over that delivered to the ejector E through the pipe p and past the check valve x. It will be understood that either of the valves x or z may be omitted; or they may 70 be used complementally, and that either may first respond to the first increment of excess exhaust steam, and the other open upon further increase in the amount of exhaust steam. 75

The air and uncondensed elastic fluid is delivered from the condenser F through the pipes e¹ to the suction chambers f¹ of the ejectors E¹, each constituting a first stage 80 ejector co-acting with a second stage ejector E². The ejectors E¹ may be of any suitable type, and are here indicated as tubular ejectors. Similarly, the ejectors E² may be of any suitable type, and are here indicated as of the radial flow type, such, for example, as 85 disclosed in Letters Patent of the United States No. 1,282,595.

Steam, as live steam, for the ejectors E¹ and E², is delivered through pipes g¹, controlled by valves h¹, the steam dividing, part 90 being delivered to the radial expansion nozzles of ejectors E² and part being delivered through the pipes i¹, i² to the nozzle structures of the ejectors E¹.

Each ejector E¹ discharges the air at still 95 higher pressure in mixture with motive steam into one-half of the condenser G comprising groups of tubes through which the discharge passes downwardly and then upwardly, the condensed steam or condensate 100 being collected in the condensate-collecting chambers j¹, from which it is drawn off through the pipes k¹ and pipe m¹ to the hot well B or condensate pipe g of the main condenser C. The air and uncondensed elastic 105 fluid pass through the pipe n¹ to the suction of the ejector E², where they are raised still further in pressure and discharged in mixture with the motive steam through the pipe o¹ into the surface condenser H, where they 110 pass around the water conducting tubes, and the steam and other condensable vapors are condensed and the air discharged to atmosphere through the port p¹. The condensate collects in the hot well q¹ and is 115 drawn through the pipe r¹ and pipe m¹ into the hot well B or condensate pipe g¹ of the main condenser, or may be delivered to any other suitable or desired destination.

The cooling medium for the condenser G 120 may be derived from any suitable source, as may be that for the condenser H. As here illustrated, however, the condensate-removal pump P delivers the condensate from the main condenser, and such condensate as may be admixed therewith from the condensers F, G, H, or any of them, through the pipe h into the cooling water space around the tubes of the condenser G, and thence through the pipe s¹ to the cooling water box t¹ of the 125 130

surface condenser H, and is discharged therefrom through the pipe w^1 to any suitable or desirable destination.

By the system described, the ejector or 5 augmenter E, by employment of exhaust steam, raises the air exhaustd from the condenser C from a vacuum of 29 inches of mercury, more or less, to a vacuum of 28 inches of mercury, more or less. The air is 10 then raised in succession by the ejectors E¹ and E² through suitable greater steps of pressure change until the air reaches atmospheric pressure or somewhat higher, or less than atmospheric pressure, as may be suitable or desirable.

By so employing the ejector E, the amount of live or high pressure motive steam employed by the ejectors E¹ and E² is materially or greatly economized, and economy is also 20 effected by employment of the condensers F, G and H, and particularly F and G, whereby the ejector E¹ is not required to compress the motive steam discharged by the ejector E, and the ejector E² is not required to compress the motive steam discharged by the ejector E¹.

The system as a whole effects efficiency in motive fluid consumption in the vacuum-producing ejectors, and the augmenter or 30 preliminary ejector E consumes only exhaust steam, which need be no more in quantity than the minimum delivered by the turbine or other motor T when running under its minimum load.

The pressure of the exhaust steam delivered through the pipe o to the ejector E may be, for example, from about three to five pounds above atmospheric pressure; while the live steam employed as the motive fluid 40 in the ejectors E¹ and E² may have a pressure from about seventy pounds upwards to one hundred fifty pounds, or higher, above atmospheric pressure.

By so employing exhaust steam to preliminarily raise the pressure of the air or other elastic fluid to be compressed through a small range of absolute pressure, though the ratio of compression of the ejector E is relatively great because, for example, increasing the absolute pressure of the air to approximately double that magnitude, the amount of live or high pressure steam employed as the motive fluid in the ejectors E¹ and E² is approximately halved, and this 50 saving is effected by exhaust steam of relatively small value for any other purpose.

With a pressure of about one inch mercury absolute in the condenser C, if the ejector E increases that absolute pressure to two 60 inches, the ratio of compression of ejector E is two. The ejectors E¹ and E² in series with each other then further raise the pressure to atmospheric pressure, the ratio of compression of the combined ejectors E¹ and E² being then fifteen, and this ratio of com-

pression may be divided between the two ejectors E¹ and E², as may be suitable or desirable; it is preferred, however, that the ratio of compression of the ejector E¹ be greater than the ratio of compression of the 70 ejector E². Furthermore, it is preferred, as regards the ejectors E¹ and E², that their ratios of compression and motive steam consumptions be in accord with my prior Letters Patent No. 1,283,593. 75

While I have described ejector E as operable with a minimum amount of exhaust steam delivered from the motor or turbine T, it will be understood that ejector E may be of such size or capacity as to use a greater 80 amount of exhaust steam, for example, an amount sufficient to cause the ejector E to have a ratio of compression greater than two, as, for example, three or more, in which case, with one inch absolute pressure in the condenser C, the suction pressure of the ejector E¹ will be an absolute pressure of three 85 inches of mercury.

It will be understood that while I have shown two ejectors E¹ and E² in series after 90 the ejector or augmenter E, a single stage ejector may be employed in lieu of E¹ and E²; for example, in lieu of a pair of serially connected ejectors E¹ and E² there may be employed an ejector of the character disclosed in my prior Letters Patent No. 1,388,670. It will be further understood that in lieu of either or both of the ejectors E¹, E² there may be employed a mechanical air 95 pump or air pump of any other type, or a 100 series of them.

What I claim is:

1. An ejector system comprising an 105 ejector employing as motive fluid low pressure or exhaust steam, and a pair of ejectors in series with each other and with said first named ejector employing as motive fluid high pressure steam.

2. An ejector system for compressing 110 elastic fluid from a pressure of approximately one inch mercury absolute to substantially atmospheric pressure, comprising an ejector employing exhaust steam as motive fluid, ejectors serially related with each other and said ejector and employing high pressure motive fluid, and a condenser between said ejector and said first named ejectors for condensing the motive steam from the mixture discharged by said first named ejector. 115

3. An ejector system for compressing 120 elastic fluid from a pressure of approximately one inch mercury absolute to substantially atmospheric pressure, comprising an ejector employing exhaust steam as motive fluid, ejectors serially related with each other and said ejector and employing high pressure motive fluid, the ratio of compression of said first named ejector being approximately two, and a condenser between said 125 130

first named ejector and said ejectors for condensing the motive steam from the mixture discharged by said first named ejector.

4. An ejector system comprising an ejector employing as motive fluid low pressure or exhaust steam, and a pair of ejectors in series with each other and with said first named ejector employing as motive fluid high pressure steam, and a condenser between said first named ejector and the first of said pair of ejectors for condensing the motive steam from the mixture discharged by said first named ejector.

5. An ejector system comprising an ejector employing as motive fluid low pressure or exhaust steam, a pair of ejectors in series with each other and with said first named ejector employing as motive fluid high pressure steam, and a condenser between the ejectors of said pair for condensing the motive steam from the mixture discharged by the first ejector of said pair.

6. An ejector system comprising an ejector employing as motive fluid low pressure or exhaust steam, a pair of ejectors in series with each other and with said first named ejector employing as motive fluid high pressure steam, a condenser between said first ejector and the first ejector of said pair, and a second condenser between the ejectors of said pair, said condensers condensing the motive fluid from the mixtures discharged thereinto.

7. An ejector system comprising an ejector employing as motive fluid low pressure or exhaust steam, a pair of ejectors in series with each other and with said first named ejector employing as motive fluid high pressure steam, the ratio of compression of said first named ejector being approximately two.

8. An ejector system comprising an ejector employing as motive fluid low pressure or exhaust steam, a pair of ejectors in series with each other and with said first named ejector employing as motive fluid high pressure steam, the ratio of compression of said first named ejector being approximately two, and the ratio of compression of the first of said pair of ejectors being greater than the ratio of compression of the other ejector of said pair.

9. The combination with an ejector, of a steam-operated motor, means for conducting steam exhausted by said motor to the nozzle structure of said ejector, a steam supply for said motor, a speed responsive governor operated by said motor and controlling the supply of steam to said motor, and a valve controlled by said governor controlling diversion of exhaust steam of said motor from said nozzle structure.

10. An ejector system comprising an ejector having nozzle structure utilizing low pressure or exhaust steam of predetermined amount, an air pump to which said ejector

delivers for further raising the pressure of the elastic fluid acted upon by said ejector, a condenser intervening between said ejector and said pump, and automatic means for diverting from the nozzle structure of said ejector into said condenser steam in excess of said predetermined amount.

11. An ejector system comprising an ejector having nozzle structure utilizing low pressure or exhaust steam of predetermined amount, an air pump to which said ejector delivers for further raising the pressure of the elastic fluid acted upon by said ejector, a condenser intervening between said ejector and said pump, a connection from the steam supply to said condenser, and a valve operable upon occurrence of excess steam supply for diverting the excess steam from the nozzle structure of said ejector into said condenser.

12. The combination with an ejector, of a steam-operated motor, means for conducting the steam exhausted by said motor to the nozzle structure of said ejector, valve structure for diverting exhaust steam from said nozzle structure, and means responsive to change of speed of said motor for causing said valve to move toward closed position.

13. The combination with an ejector, of a steam-operated turbine, means for conveying steam exhausted by said turbine to the nozzle structure of said ejector, an automatic governor controlling admission of steam to said turbine, and valve structure controlled by said governor for diverting exhaust steam from the nozzle structure of said ejector.

14. The combination with an ejector, of a steam-operated motor, means for conducting the steam exhausted by said motor to the nozzle structure of said ejector, valve structure for diverting exhaust steam from said nozzle structure, means responsive to increase of speed of said motor for causing said valve to move toward closed position, and additional automatic means responsive to excess exhaust steam for diverting exhaust steam from the nozzle structure of said ejector.

15. The combination with an ejector, of a steam-operated turbine, means for conveying steam exhausted by said turbine to the nozzle structure of said ejector, an automatic governor controlling admission of steam to said turbine, valve structure controlled by said governor for diverting exhaust steam from the nozzle structure of said ejector, and additional automatic means responsive to excess exhaust steam for diverting exhaust steam from the nozzle structure of said ejector.

16. The combination with an ejector, of a steam-operated motor driving a variable load, means for conducting the steam exhausted by said motor to the nozzle struc-

- ture of said ejector, said ejector operable by the steam exhausted by said motor when its load is substantially a minimum, and automatic means for diverting from the nozzle structure of said ejector excess steam exhausted by said motor when the load thereof is substantially greater than said minimum load.
17. The combination with a condenser, of a steam-operated motor driving the apparatus auxiliary to said condenser, and means for producing a vacuum in said condenser comprising an ejector, and means for conducting the steam exhausted by said motor to the nozzle structure of said ejector, said ejector being operable by substantially the minimum amount of steam exhausted by said motor corresponding substantially with the minimum amount of steam delivered to and condensed by said condenser.
18. The combination with a condenser, of a steam-operated motor driving the apparatus auxiliary to said condenser, an ejector and an air pump serially related therewith, and means for conducting the steam exhausted by said motor to the nozzle structure of said ejector, said ejector being operable by substantially the minimum amount of steam exhausted by said motor corresponding substantially with the minimum amount of steam delivered to and condensed by said condenser.
19. The combination with a condenser, of a steam-operated motor driving the apparatus auxiliary to said condenser, and means for producing a vacuum in said condenser comprising an ejector, means for conducting the steam exhausted by said motor to the nozzle structure of said ejector, said ejector being operable by substantially the minimum amount of steam exhausted by said motor corresponding substantially with the minimum amount of steam delivered to and condensed by said condenser, and means for automatically diverting excess steam exhausted by said motor.
20. The combination with a condenser, of a steam-operated motor driving the apparatus auxiliary to said condenser, an ejector and an air pump serially related therewith, means for conducting the steam exhausted by said motor to the nozzle structure of said ejector, said ejector being operable by substantially the minimum amount of steam exhausted by said motor corresponding substantially with the minimum amount of steam delivered to and condensed by said condenser, a condenser intervening between said ejector and said ejector apparatus, and means for diverting into said condenser steam exhausted by said motor in excess of the amount utilized by said ejector.
21. The combination with a main condenser, of a steam-operated motor for driving the apparatus auxiliary to said condenser, means for producing a vacuum in said condenser comprising an ejector and ejector apparatus into which said ejector discharges, means for delivering to the nozzle structure of said ejector steam exhausted by said motor, said ejector being operable by substantially the minimum amount of steam exhausted by said motor corresponding with substantially minimum load upon said motor, and means for supplying high pressure steam to the nozzle structure of said ejector apparatus.
22. The combination with a main condenser, of a steam-operated motor for driving the apparatus auxiliary to said condenser, means for producing a vacuum in said condenser comprising an ejector and ejector apparatus into which said ejector discharges, means for delivering to the nozzle structure of said ejector steam exhausted by said motor, said ejector being operable by substantially the minimum amount of steam exhausted by said motor corresponding with substantially minimum load upon said motor, means for supplying high pressure steam to the nozzle structure of said ejector apparatus, and means for diverting steam exhausted by said motor in excess of said minimum amount.
23. The combination with a main condenser, of a steam-operated motor for driving the apparatus auxiliary to said condenser, means for producing a vacuum in said condenser comprising an ejector and ejector apparatus into which said ejector discharges, means for delivering to the nozzle structure of said ejector steam exhausted by said motor, said ejector being operable by substantially the minimum amount of steam exhausted by said motor corresponding with substantially minimum load upon said motor, means for supplying high pressure steam to the nozzle structure of said ejector apparatus, a condenser intervening between said ejector and said ejector apparatus, and means for diverting into said condenser steam exhausted by said motor in excess of the amount utilized by said ejector.
24. The combination with a condenser, of a pump for removing the condensate therefrom, a steam-operated motor for driving said pump, apparatus for producing a vacuum in said condenser comprising an ejector, means for conducting to the nozzle structure of said ejector steam exhausted by said motor, said ejector being operable by substantially the minimum amount of steam exhausted by said motor corresponding with substantially the minimum amount of steam delivered to said condenser, and automatic means for diverting steam exhausted by said motor in excess of said minimum amount.
25. The combination with a main condenser, of a pump for removing the condensate therefrom, a steam-operated motor for

- driving said pump, apparatus for producing a vacuum in said condenser comprising an ejector and an air pump in series therewith, means for conducting to the nozzle structure of said ejector steam exhausted by said motor, said ejector being operable by substantially the minimum amount of steam exhausted by said motor corresponding with substantially the minimum amount of steam 5 delivered to said main condenser, a condenser between said ejector and said pump, and means for diverting into said last named condenser steam exhausted by said motor in excess of said minimum amount 10 utilized by said ejector.
26. The combination with a main condenser, of a steam-operated motor driving the apparatus auxiliary to said condenser, means for producing a vacuum in said condenser 15 comprising serially connected ejectors, a condenser intervening between said ejectors, and a condenser into which the second of said ejectors discharges, a pump driven by said motor removing condensate 20 from said main condenser and delivering it as cooling medium into said condenser into which the second ejector discharges, and means for conducting steam exhausted by said motor to the nozzle structure of said 25 first ejector.
27. The combination with a main condenser, of a steam-operated motor driving the apparatus auxiliary to said condenser, means for producing a vacuum in said condenser 30 comprising serially connected ejectors, a condenser intervening between said ejectors, and a condenser into which the second of said ejectors discharges, a pump driven by said motor removing condensate 35 from said main condenser and delivering it as cooling medium into said condenser into which the second ejector discharges, means for conducting steam exhausted by said motor to the nozzle structure of said first 40 ejector, and means for diverting into the condenser into which said first ejector discharges steam exhausted by said motor in excess of that required by said first named 45 ejector.
50. 28. The combination with an ejector, of an air pump in series therewith, a condenser between said ejector and said pump, means for delivering to the nozzle structure of said ejector low pressure or exhaust steam, means 55 for diverting into said condenser steam in excess of that required by said ejector, and means for effecting condensation in said condenser by boiler feed water.
60. 29. The combination with a main condenser, of a condensate pump therefor, a steam-driven motor driving said pump, an ejector for withdrawing air from said condenser, means conducting steam exhausted by said motor to the nozzle structure of said 65 ejector, a second ejector, a condenser inter-

vening between said ejector and said second ejector, a third ejector, a condenser intervening between said second and third ejectors, and a condenser into which said third ejector discharges, said pump delivering condensate of said main condenser to said last named condenser and the condenser intervening between said second and third ejectors. 70

30. The combination with an ejector, of an air pump in series therewith, a condenser between said ejector and said pump, means for delivering to the nozzle structure of said ejector low pressure or exhaust steam, and means for effecting condensation in said condenser by boiler feed water. 75

31. The combination with an ejector, of a steam-operated motor, means for conducting low pressure steam from said motor to the nozzle structure of said ejector, valve structure for diverting low pressure steam from said nozzle structure, and means responsive to change of speed of said motor for controlling said valve. 85

32. The combination with an ejector, of a steam-operated motor, means for conducting low pressure steam from said motor to the nozzle structure of said ejector, a condenser into which said ejector discharges, and valve structure for diverting low pressure steam from said motor into said condenser. 95

33. The combination with an ejector, of means for delivering to the nozzle structure thereof low pressure steam, means for diverting from said nozzle structure low pressure steam in excess of that required by said ejector, and means for effecting condensation of the diverted low pressure steam and the steam discharged by said ejector by make-up boiler feed water. 100

34. The combination with an ejector, of an air pump in series therewith, a condenser between said ejector and said pump, means for delivering to the nozzle structure of said ejector low pressure steam, means for diverting into said condenser low pressure steam in excess of that required by said ejector, and means for effecting condensation of the diverted steam and the steam exhausted by said ejector by make-up boiler feed water. 110

35. The combination with an ejector, of an air pump in series therewith, a condenser between said ejector and said pump, means for delivering to the nozzle structure of said ejector low pressure steam, and means for effecting condensation of the motive fluid of said ejector in said condenser by make-up boiler feed water. 120

In testimony whereof I have hereunto affixed my signature this 1st day of February, 1922.

ROBERT SUCZEK.

Certificate of Correction.

It is hereby certified that in Letters Patent No. 1,522,155, granted January 6, 1925, upon the application of Robert Suczek, of Philadelphia, Pennsylvania, for an improvement in "Ejector Systems," an error appears in the printed specification requiring correction as follows: Page 3, line 117, claim 2, strike out the words "first named" and insert the same before the word "ejector" in the same line and claim; and that the said Letters Patent should be read with this correction therein that the same may conform to the record of the case in the Patent Office.

Signed and sealed this 28th day of April, A. D. 1925.

[SEAL.]

KARL FENNING,
Acting Commissioner of Patents.
